Specification for Design.

Patented Sept. 28, 1915.

Application filed July 2, 1915. Serial No. 37,772. Term of patent 14 years.

To all whom it may concern:

Be it known that I, WILLIAM J. H. STRONG, a citizen of the United States, residing at Beloit, in the county of Rock and State of Wisconsin, have invented a new, original, and ornamental Design for the Base of a Motor-Driven Fan, of which the following is a specification, reference being had to the accompanying drawing, forming a part thereof.

Figure 1 is a side elevation of a base for a motor-driven fan, showing my new design. Fig. 2 is a top plan view of said base.

I claim:

The ornamental design for a base for a motor-driven fan, as shown.

WM. J. H. STRONG.
